CABINET FOR RADIO RECEIVING SETS
Lester K. Franklin, 390 S. Hauser Blvd.,
Los Angeles, Calif.
Filed May 22, 1962, Ser. No. 196,754
3 Claims. (Cl. 325—352)

This invention relates to cabinets for radio receiving sets. For example, the cabinet may simulate a harp in miniature. A set utilizing small transistors and powered by dry cells can readily be designed to fit into the narrow converging space defined by the sounding board and the back of the harp.

It is accordingly one of the objects of this invention to provide a cabinet simulating such an instrument.

This invention possesses many other advantages, and has other objects which may be made more clearly apparent from a consideration of one embodiment of the invention. For this purpose, there is shown a form in the drawings accompanying and forming a part of the present specification, and which drawings, unless as otherwise indicated, are true scale. This form will now be described in detail, illustrating the general principles of the invention; but it is to be understood that this detailed description is not to be taken in a limiting sense, since the scope of this invention is best defined by the appended claims.

Referring to the drawings:

FIGURE 1 is a side elevation of a radio cabinet embodying the invention, and shown as assembled with a miniature radio receiving set;

FIG. 2 is an elevation taken from the right hand side of FIG. 1;

FIG. 3 is a bottom view thereof;

FIG. 4 is a fragmentary, enlarged sectional view, showing the simulated sounding board and back of the cabinet; and

FIGS. 5, 6 and 7 are sectional views, taken along planes respectively corresponding to lines 5—5, 6—6 and 7—7.

The cabinet in this instance simulates a miniature harp. This miniature harp may include a pedestal 1, a pillar 3, a capital 4, a sounding board 5, a back 6 and a neck 7.

Pins 8 simulate the pins to which the strings 9 may be fastened. In this case the strings are simulated by the threads or cords between the neck 7 and the sounding board 5.

As shown most clearly in FIG. 4, the strings 9 are anchored in any appropriate manner to the sounding board 5. For example, a strip 16 of metal may overlie the central portion of the board 5; the threads 9 pass through apertures in the strip and are held tightly to the board 5 by the overlying strip 16.

The right hand end of neck 7 has a downwardly curved portion 11 attached as by appropriate fastening means to the upper surfaces of a block 10 and the back 6. The back 6 is attached to the block 10 by the aid of wood screws 12.

As shown most clearly in FIGS. 2, 5 and 6, the back 6 is provided with a series of oval openings 13. A screen 35 covers these openings. The back 6 has edges 14 diverging downwardly so that at the bottom of the cabinet the back 6 is wider than at the top. This is evident from a comparison of FIGS. 5 and 6.

Similarly, the sounding board 5 widens toward the base. Side elements 15 connect the elements 5 and 6. In this way a space is formed bounded by the four sides

2

5, 6 and 15 defining a quadrilateral. The sides 15 converge toward the base.

The pillar 3 is attached to the left hand end of the neck 7. The lower end is supported on the pedestal 1. This pedestal is appropriately formed of a symmetrical multiple-sided element shown to best advantage in FIG. 7, including the wood panels 17, 19, 20, 21, 22, 23 and 24 appropriately joined together. Simulated pedals 40 extend from each of the elements 17 and 23.

10 Triangular shaped corner pieces 25 may be provided at the corners between the elements 17 and 24, and between the elements 23 and 24. The elements 17 and 23 converge toward the element 24. Similarly, a corner piece 26 joins the two parts 20 and 21.

15 The space 27 within pedestal 1 is intended to accommodate a miniature loud speaker 28 having its open side directed downwardly and supported upon a bottom closure member 29. This bottom closure member is apertured as indicated by reference character 30 for the emission of sound waves generated by the loud speaker 28.

20 The pedestal 1 is provided with feet 31 so as to leave a space between the supporting surface and the bottom of the loud speaker, through which sound waves can flow.

25 The hollow space defined by the sounding board 5 and the back 6 converges upwardly toward the neck 7 and accommodates the appropriately designed radio set 32. This radio set is shown in phantom lines in FIGS. 4, 5 and 6. The removal and replacement of the set require no manipulation of fastening means, since the loud speaker 28 serves to confine and lock the set within the wedge-shaped space. Control buttons 33 and 34 project outwardly of the elements 15 and provide on-off switching, volume and tuning controls. They operate appropriate shafts passing through the sides 15.

30 Any one of the controls, however, may be effected by utilizing the capital 4 as a knob for performing any one or more of the control functions. In such instance, the pillar 3 may be made hollow so as to make it possible to pass leads to the radio set 32.

35 Since the space formed by the sounding board 5 and back 6 communicates with the back side of loud speaker 28, sound waves from the rear of the speaker can proceed through this space and out through openings 13.

The inventor claims:

40 1. In a miniature radio receiving set: means simulating a harp, and having a simulated sounding board and back, said sounding board and back being joined by sides that converge and are tapered toward the top, said space accommodating the set; the simulated harp having a pedestal; a loud speaker in the pedestal and extending transversely of the space to limit downward movement of the set; said loud speaker being directed downwardly; said pedestal having legs to elevate the speaker above a supporting surface; said simulated harp also having a hollow pillar, and a rotary radio control knob supported on the top of the column and simulating the capital of the pillar.

45 2. A combination comprising: a case for a radio set, set case simulating a harp and having a simulated sounding board and back joined by sides that converge and are tapered toward the top to provide a space to accommodate a radio set; a hollow pedestal so joined to said simulated sounding board, back and sides that said space communicates with the interior of the pedestal, said pedestal having legs to elevate it above a supporting surface and a removable bottom with openings therein; a loud speaker in said pedestal mounted on said bottom and directed

downwardly thereon; and a radio receiving set in said space, said set resting upon said speaker; said back having openings therein for the emission of sound waves passing through said space from the interior of the pedestal.

3. The combination as set forth in claim 2 with the addition of means extending from said space through said sides to provide externally accessible controls for said set.
